UNITED STATES PATENT OFFICE.

PATRICK B. DELANY, OF NEW YORK, N. Y., ASSIGNOR TO THE STANDARD ELECTRIC MANUFACTURING COMPANY, OF SAME PLACE.

TELEGRAPHIC APPARATUS.

SPECIFICATION forming part of Letters Patent No. 286,280, dated October 9, 1883.

Application filed April 14, 1883. (No model.)

To all whom it may concern:

Be it known that I, PATRICK B. DELANY, a citizen of the United States, and a resident of the city, county, and State of New York, have 5 invented certain new and useful Improvements in Telegraphic Apparatus, of which the following is a specification.

The primary object of my invention is to prevent the chattering or singing of the sounder-armature on telegraphic lines where vibratory or rapidly-interrupted currents are employed.

In the accompanying drawings, Figure 1 is a diagrammatic plan view of two stations connected by a main line organized for transmission by means of vibratory currents. Fig. 2 is a detailed view, showing the relay sounder, key, and battery at a single station.

The system of operation disclosed in Fig. 1 is substantially the same as that disclosed in an application of duplex telegraphy filed simultaneously herewith, serially numbered 91,709, and no claim is herein made, broadly, to such a system. That figure, however, represents a system of vibratory telegraphy to which my improved organization of sounders is specially applicable.

At each of the stations X and Y, I place a circuit-breaker, in this instance shown in the drawings as a vibrating tuned fork. The fork is automatically vibrated by a local battery and circuit, (indicated by dotted lines,) in which the coils of the battery-magnet A A are placed. This local circuit is made and broken automatically between the platinum contact *a* on one of the tines of the fork, and a very delicate light platinum contact-finger carried on the end of an insulated pivoted lever, B. When the fork is started into vibration, its vibration will be automatically continued by the action of the local battery and magnets, and in order, if necessary, to regulate the speed of vibration within limits, I provide the poles of the magnet with adjustable extension-pieces.

In order to prevent sparks between the platinum contact *a* and the spring, I place a resistance, R_h, in a shunt which runs from the head of the fork to the lever B. The opposite tine of the fork is provided with platinum contact-pieces *c d*, one on each side, which alter-

nately and successively, as the fork vibrates, complete the main-line circuit through the pivoted insulated levers *e' d'* and through the lines E D, in each of which is a relay and key 55 and the main battery. The proper rates of vibration of the forks should, however, depend upon their normal rates, and not upon adjustment or modification of those rates, because it is desirable that the vibrations should be wide 60 and strong, so that the completions of the branch circuits may be entirely clear and independent of each other, as obviously the best results can be obtained in that way. The organization is identical at both stations, and if 65 the fork at station X vibrates normally—say at a rate of two hundred per second—and that at station Y at a rate of ninety per second, the circuit at station X will of course be completed through the lines E D two hundred 70 times in every second, and at station Y through the lines E D ninety times per second. At station Y the battery G in the line E is placed with its positive pole to the line, while the battery H in the line E at station X is placed 75 with its positive pole to the line, and the battery I in line D at station X, and the battery L in line D at station Y, are placed with their negative poles to the line. Under this organization two messages may be transmitted either 80 simultaneously in the same direction or simultaneously in opposite directions. Thus if the key connected to the battery I at station X is depressed and the forks at both stations are vibrating, as remarked above, the battery 85 I will send two hundred impulses per second into the main line. At station Y the circuit will be completed ninety times per second through both the lines E and D; but the relay in the line E only will be affected, because in 90 that line the battery G is not opposed to the battery I, so if the key connected with the battery H at station X is operated the current transmitted from that battery will only be effective in the line D. The operation is precisely the same if Y is the transmission end of the line. It will also be obvious that a message may be sent from station Y simultaneously with one from station X without interference.

There is always a sufficient number of vibrations per second to complete each circuit

in which the telegraphic instruments are placed a sufficient number of times to transmit telegraphically with perfect ease and accuracy, and the circuit between each pair of operators is as separate and distinct as if they each had an independent wire. In such a system, however, if ordinary sounders and local circuits are employed, there is apt to be an annoying singing or chattering of the sounder-armature. To obviate this difficulty and give distinctly-working apparatus which gives its stroke in the ordinary way, I have devised certain improvements in the sounders and their local circuits, so that the downward reading-stroke on the sounder is given when the relay-armature leaves its back stop, instead of causing the sounder to give a reading-stroke when the relay-armature is brought against its front stop, as has heretofore been the case in systems of this character.

In Fig. 1 each of the sounders S is arranged in the following manner: The coil of the sounder is placed in a closed local circuit, but the poles of the local battery are also connected with the relay-armature and its back stop. When, therefore, there is no impulse of electricity in the main line, the relay-armature will be drawn by its spring against the back contact, and the local battery will be shunted from the sounder-coil, and the armature of the sounder will of course be drawn by its spring against its back stop. When an impulse of electricity, however, is received, the relay-armature is drawn away from its back stop, and the moment it leaves that stop the shunt is broken and the current from the local battery traverses the coils of the sounder and causes its armature to give its ordinary downward reading-stroke. As the shunt or the local circuit is broken the moment the relay-armature leaves its back stop, the subsequent movement of the relay-armature, or its vibration or chattering on its front stop, does not affect the sounder. With such an organization, therefore, the sounder works as distinctly as if a strong continuous current were used. Of course this special arrangement may be used with equal advantage upon long Morse circuits, where the electro-motive force at the receiving-station is so diminished by leakage or other causes that the current is too weak to hold the relay-armature firmly in contact with its front stop against the pull of its spring.

In Fig. 2 I have shown a sounder which, although different in construction and arrangement of circuit from that just described, operates in the same manner—that is, the ordinary downward reading-stroke upon the sounder is given when the relay-armature leaves its back stop. To describe the arrangement illustrated in this figure more in detail, the local-battery circuit is completed through the relay-armature, its back stop, and the coil of the sounder. The reading-stroke of the sounding-armature

is the attraction of the sounder-magnet. When there is no current on the line, the relay-armature is drawn over against its back stop by its tension-spring, and the local circuit is completed through the coil of the sounder, and the armature of the sounder is lifted from the sounding-bridge against the tension of its spring by the sounder-magnet. When an impulse of electricity is received over the line, the relay-armature leaves its back stop, and the moment it leaves that stop the local-sounder circuit is broken, and the sounder-armature is drawn down upon the bridge by the force of the spring. The subsequent vibration of the relay-armature on its front stop, or any movement of it between the front and back stops, will not affect the sounder. It is obvious that such an arrangement is applicable to the system illustrated in Fig. 1, or to any system where vibratory currents are employed.

As above remarked, I am aware that in the organization shown in Fig. 1 the local circuit is shunted and not broken, and the downward reading-stroke of the sounder-armature is given by the attraction of the sounder-magnet, which overcomes the pull of the sounder-armature spring, and that in Fig. 2 the local circuit is not shunted, but is broken, and the reading-stroke on the sounder on the sounding-bridge is given by the pull of the spring, and not by the attraction of the magnet. In both organizations, however, the arrangement is such that the sounder gives the ordinary downward reading-stroke when the relay-armature leaves its back stop, and not when it makes contact with its front stop.

The right to file hereafter other applications covering, broadly, the sounder which gives the spring-stroke, or any subjects matter herein shown or described and not fully claimed, is reserved.

I claim as my invention—

1. The combination, with a system of telegraphy in which each signal or working-impulse is made up of a series of vibrations or impulses, of a relay and sounder so arranged that the sounder gives its reading-stroke when the relay-armature leaves its back stop.

2. The combination, with a system of telegraphy in which each signal or working-impulse is made up of a series of vibrations, of a relay, a sounder local circuit which is closed when the relay-armature is at rest, the normally-attracted sounder-armature, and a spring which causes the downward reading-stroke of said armature when the relay-armature leaves its back stop.

In testimony whereof I have hereunto subscribed my name this 12th day of April, A. D. 1883.

PATRICK B. DELANY.
